UNITED STATES PATENT OFFICE.

SAMUEL B. ZIMMER, OF LOS ANGELES, CALIFORNIA, ASSIGNOR TO GERTRUDE E. ZIMMER, OF LOS ANGELES, CALIFORNIA.

WINDOW CONSTRUCTION.

Application filed September 5, 1923. Serial No. 661,044.

To all whom it may concern:

Be it known that I, SAMUEL B. ZIMMER, a citizen of the United States, residing at Los Angeles, in the county of Los Angeles and State of California, have invented new and useful Improvements in Window Construction, of which the following is a specification.

My present invention is a novel window construction, and it is an especial object of this invention to provide a window whose casing and sash frames shall both be formed of metal, and which shall nevertheless be especially adapted to use in school buildings, or the like, in which both adequate illumination and adequate ventilation may be required.

It is an object of this invention to provide a fireproof window construction comprising a casing which may be formed of sheet metal in a manner adapting the same to be employed either in wooden buildings or in stone or concrete or other buildings; and it is a further object of this invention to associate with the mentioned sheet metal casings, each section of which may be formed either from a single piece of sheet metal or from a plurality of pieces suitably bent and associated as hereinafter described, sash frames preferably formed of T-bars and adapted to interfit therewith.

It is a further object of my invention to provide a window comprising a pair of counterbalanced sash capable of movement in a common plane and preferably associated with two additional sash, one of which may be positioned above the said pair of counterbalanced sash and offset relatively thereto, the other additional sash being preferably placed below the mentioned pair of counterbalanced sash and offset in an opposite direction, the last mentioned sash being optionally pivoted on a horizontal axis and in such manner as to permit of its employment as a deflecting plate, effective to prevent a direct draft upon, for example, a pupil who may be seated near the same.

It is a further object of my invention to provide a casing adapted to guide counterbalanced sash of the character referred to and partially or completely to house a suitable pulley and a chain or other flexible element by which such sash may be connected; and my preferred construction may com-

prise also a lock by which the respective sash may be securely but releasably connected at will, and also suitable lip members, preferably in the form of angle irons, adapted to form a weather-tight joint between the respective counterbalanced sash and the additional sash arranged above and below the same, as already mentioned.

Other objects of this invention, including the use of metal sash whose lateral elements are arranged in a common vertical plane, and the use of a removable stop on the mentioned metal casings or jambs, will be appreciated upon a perusal of the following description and the appended claims, taken in connection with the accompanying drawings, in which—

Fig. 1 is a rear elevation, showing parts of a window comprising four sash and a portion of the jamb or casing contiguous thereto, parts being broken away. 75

Fig. 2 is a corresponding vertical section taken at right angles to Fig. 1, and showing diagrammatically the intended relationships of the respective sash referred to. 80

Fig. 3 may be regarded as a somewhat diagrammatic section on a line such as the line 3—3 of Fig. 2, and showing not only the respective sash but a preferred construction of sheet metal jamb or casing as the same may be employed in a wooden building. 85

Fig. 4 is a similar showing but indicating the adaptation of my metallic window construction to use in a concrete or other fireproof building. 90

Fig. 5 is a similar section, but showing the use of a two-part sheet metal jamb. 95

Referring in detail to the parts of that specific embodiment of my invention shown in Figs. 1—4, 1 may be a jamb comprising the usual four elements connected to form a rectangular frame or opening and shown as preferably provided upon its front or exterior surface with a plurality of offsets A, B and C, and at its rear surface with corresponding offsets A', B' and C', the respective parallel surfaces A and A' being spaced apart a distance adapting my jamb to be used in either a wooden or a concrete building, and the space between the parallel surfaces B and B' being preferably approximately equivalent to the length of an ordinary brick, whereas the distance between the surfaces C and C' may correspond approxi-

mately to the length of the "stem" section of a T-bar 2, from which the respective sash comprised in my window may be formed.

When jambs of my preferred design are to be embodied in a wooden building, a suitable relationship thereof to the vertical studs 3 and the sheathing elements 4 being suggested in Fig. 3, the respective jambs may be secured by means such as the nails 5, 10 which may be covered in any suitable way, as by strips 6.

When my novel jambs are to be used in connection with sash of my preferred design, comprising the mentioned T-bars suitably cut and bent or secured at their corners, it will be understood that the uppermost sash 7 may occupy an outermost position, as best shown in Fig. 2, one portion of a T-bar 2 then overlying the surface C while another 20 portion, constituting the stem of the T, contacts with the innermost surface D of a jamb. The pair of counterbalanced sash 8, 8' being then so arranged as to facilitate a relative movement in a plane parallel with 25 the plane of the uppermost sash 7. I may provide flexible means such as the chain 9, shown as passing over a pulley 10 arranged to rotate in the same plane as said sash and as secured in the transom bar or frame head 30 11, one end of this chain being shown as secured to the sash 8 by a hook 12, and the other end thereof being housed in a chain pocket 13, formed by securing a suitably bent and cooperating piece of sheet metal 35 constituting a removable stop 14 to the face E of the jamb 1, as best shown in Fig. 3; and the return lap of the mentioned chain may be secured at 15 to the lower counterbalanced sash 8', in such manner that whenever 40 movement is imparted to either the sash 8 or the sash 8', an opposite movement must be transmitted to the other of these counterbalanced sash—which are shown as provided with an easily releasable lock 16, and with a 45 lip member 17, shown as secured to movable sash 8, in order to exclude the weather.

The lowermost sash 18 of the four sashes which I prefer to employ in each complete window is preferably pivoted, as at 19, upon 50 a horizontal pivot, and in such manner as to permit the top of the same to swing inward, thereby providing an upwardly inclined wind-deflecting surface, adapted, in a known manner, to permit of the ventilation of a 55 room without causing an undesirable draft. This lowermost sash 18, when closed, may be adapted to abut against the surface F of the housing element 14, which serves also to 60 guide or retain the respective counterbalanced sash and to provide the mentioned chain pocket 13. The uppermost sash 7 being permanently secured in any suitable way, as by means of bolts 20, and the pivoted sash 18 being secured by means of the hinges 65 19, and the respective counterbalanced sash

being secured and guided in the manner described, and provided with the mentioned lip 17, it will be obvious that the additional lip elements 21 and 22, secured respectively to the uppermost of the counterbalanced sash 70 and to the pivoted sash 18, each of these elements being preferably in the form of a section of angle iron, all cooperate with one another and with the described jamb construction to effect a weather-tight window 75 construction which is adapted for use in various types of building and in the providing of light and air by means of openings of any desired size.

One mode of adaptation of my casement construction to employment in a concrete building is suggested in Fig. 4, a concrete wall being indicated at 23, and suitable projections, such as bricks 24 embedded in the concrete and properly aligned to fill the interval between the parallel faces B and B' 80 of my jamb being indicated at 24. An alternative mode of bending the sheet metal is also indicated in this figure.

In Fig. 5 I have shown an alternative type 85 of jamb, suitable for use in connection with various types of windows comprising a pair of counterbalanced sash and one or more additional sash placed above or below the same, the jamb being, however, in this case formed of two sections 25 and 26, adapted to be secured to a wooden stud 27 by means such as the screws 28, and together constituting a pocket 29 for the chain 9 secured at 15 to a counterbalanced sash 8', this sash being guided by the extension of one branch 90 of the T-bar which constitutes its stile through a gap or opening 30 between the respective sheet metal sections 25 and 26 100 constituting my two-part jamb.

From one point of view, all types of jamb herein referred to may properly be characterized as two-part jambs, it being understood that the jambs referred to in Figs. 1-4 105 comprise removable stop elements which may constitute complete subsidiary frames, and the jamb shown in Fig. 5 may be regarded as consisting of two complete frames separated by the gap or slot 30, into which 110 extend lateral wings or extensions 31, integral with the stiles 32, formed of T-bars; and these T-bar stiles may be permitted either to contact with one another, in the manner best shown in Fig. 3, or they may be arranged to contact with suitable fins 33, 33', shown as formed upon the respective jamb frames 34, 35, which are shown in Fig. 4 as secured together by screws 36.

It is a notable advantage of the type of 115 jamb construction shown in Fig. 5 that the respective jamb frames 25 and 26 may be separately brought, from opposite directions, into position upon opposite faces of a wall provided with a suitable window opening; and among the further notable 120 130

advantages of my described construction are the facts that my jambs may be used either alone or with a backing of rough lumber, or the like, and the fact that the 5 construction of these jambs is such as completely to obviate the necessity for a premature or factory assembly of all sash within the respective jambs,—it being entirely possible to handle my jamb frames and my 10 sash as separate units, which may optionally be provided at the factory or elsewhere with suitable coatings of enamel or protective metal, or the like, and which may thereafter be assembled on a job, in substantially 15 the same way that wooden jambs and sash have heretofore been put in place. The movable stops or frames 14 and 25 and 35 are of course intended to be adjusted to their proper position after the counterbalanced 20 sash are hung, in a manner permitting lips 21, 22 to overlie rails 37, 38.

Although one or more pair of counterbalanced sash of my improved design may 25 obviously be associated with any desired number of fixed or movable additional sash, I consider it distinctly advantageous to 30 adapt my sash to separate in opening, and also distinctly advantageous, both from the standpoint of economy in glazing and from 35 the standpoint of resulting artistic appearance, to employ sash of uniform dimensions and having an even sash or putty line throughout, my preferred construction being such that the respective sash may be brought at will into substantial coincidence, with their corresponding stiles in a common 40 vertical plane at right angles to the planes of the sash.

Although I have herein described one 45 complete embodiment of my invention, suggesting also various modifications and specific applications thereof, it should be understood not only that numerous features of my invention are capable of independent use but also that various additional modifica-

tions thereof might be made by those skilled in the art without departing from the spirit and scope of my invention as the same is indicated above and in the following claims.

What I claim is:

1. In a window, a pair of oppositely movable sash arranged in the same vertical plane and supported by a flexible element, one lap of which is concealed in a housing formed of sheet metal and constituting a removable 55 stop.

2. A window construction comprising a window frame having at least four equally sized sash therein arranged in three parallel planes, the central plane of which is determined by stops and contains two centrally located sash, means for counterbalancing said centrally located sash, and means for separating said centrally located sash whereby they may assume positions coincident 60 with each of the remaining sash.

3. A window construction comprising at least four equally sized sash within a frame, said frame having side jambs forming a guideway for two of the said sash which 65 are centrally located, means for counterbalancing said centrally located sash, said means permitting said sash to separate, whereby said centrally located sash assume 70 positions coincident with the remaining sash.

4. A window construction including three sash, two of which are slidable in the same plane, and the remaining sash being mounted for pivotal movement and disposed in a different but parallel plane.

5. A window construction including a first sash arranged in one plane, a pair of sash slidably mounted in a second parallel plane, and a fourth sash disposed in a third parallel plane, said fourth sash being pivotally mounted to swing out of its respective 85 plane.

In testimony whereof I have signed my name to this specification.

SAMUEL B. ZIMMER.
